CLAIM

The ornamental design for a writing instrument, as shown and described.

DESCRIPTION

FIG. 1 is a front perspective view of a writing instrument showing my new design;

FIG. 2 is a right side elevational view thereof;

FIG. 3 is a front elevational view of my design as translucent;

FIG. 4 is a back side elevational view thereof;

FIG. 5 is a left side elevational view thereof;

FIG. 6 is a bottom plan view thereof; and,

FIG. 7 is a top plan view.

The inside features and writing tip in broken lines are included to show portions of the writing instrument that form no part of the claimed design.

1 Claim, 6 Drawing Sheets
